DESIGN FOR WALL-PAPER.

Design No. 12,571, dated November 15, 1881.

UNITED STATES PATENT OFFICE.

EDUARD LEISSNÈR, OF NEW YORK, N. Y., ASSIGNOR TO LEISSNÈR & LOUIS, OF SAME PLACE.

DESIGN FOR WALL-PAPER.

SPECIFICATION forming part of Design No. 12,571, dated November 15, 1881.

Application filed August 25, 1881. Term of patent 3½ years.

To all whom it may concern:

Be it known that I, EDUARD LEISSNÈR, of New York city, in the county and State of New York, have invented a new and original Design for Wall-Paper, of which the following is a specification.

This invention relates to a new and original design for wall-paper and similar fabrics; and it consists in the novel grouping and configuration of parts hereinafter more fully described.

The accompanying photograph illustrates a face view of a wall-paper having my new design.

Between two stripes or borders, each of which is divided into adjoining rectangles containing oval centers, is the main part of this wall-paper, which is traversed by a large stem, forming series of convolutions. In one of these convolutions is contained a large full flower, B; in another a large flower, C, having cross-like pistil; in another a large flower, H, and in still another a large flower, L. Between the flowers H and L is a lesser flower, M, from which grows a stem, P, carrying flowers T and leaves

O. The convolution containing the flower L 25 carries also a cluster of small star-shaped flowers, a. Between the flowers C and H is a small flower, J, and from the convolution forming the flower C projects a stem, d, having flowers I m. The convolution which contains the flower B 30 has also further flowers, e and R.

I claim—

1. The design for wall-paper, consisting of the flower B, substantially as shown.
2. The design for wall-paper, consisting of 35 the flower C, substantially as shown.
3. The design for wall-paper, consisting of the flower H, substantially as shown.
4. The design for wall-paper, consisting of the flower L, substantially as shown.
5. The design for wall-paper, consisting of 40 the flowers B C H L and ornaments T, O, P, a, m, M, J, d, I, e, and R, substantially as shown.

EDUARD LEISSNÈR.
